UNITED STATES PATENT OFFICE.

GEORGE MARSHALL, OF PHILADELPHIA, PENNSYLVANIA.

BURGLAR ALARM.

Application filed October 21, 1924. Serial No. 744,871.

To all whom it may concern:

Be it known that I, GEORGE MARSHALL, a citizen of the United States, residing at Philadelphia, in the county of Philadelphia and State of Pennsylvania, have invented a certain new and useful Burglar Alarm, of which the following is a specification:

This invention, generally stated, relates to signals or alarms and has more especial 10 relation to a device for audibly announcing unauthorized entry to a house, apartment, store, or like place.

The leading object of the present invention may be said to reside in the providing 15 of a simple, efficient, and comparatively inexpensive article of hardware which may be readily attached to a window frame in a few moments time whereby upon raising 20 of the window by a person trying to gain unauthorized entry an audible alarm or signal is given.

A further object resides in the providing of general arrangement, construction and connection of parts for attaining the results 25 sought by the leading object.

Other and further objects not at this time appearing will be hereinafter more specifically referred to.

The invention consists of the novel construction hereinafter described and finally 30 claimed.

The nature, characteristic features and scope of the invention will be more fully understood from the following description 35 taken in connection with the accompanying drawings forming part hereof, and in which:

Fig. 1, is a fragmentary view, partly sectioned, of a window frame and complementary sash showing my burglar alarm oper- 40 atively arranged with respect to the lower sash.

Fig. 2, is a view in elevation of the burglar alarm detached.

Fig. 3, is an end view of Fig. 2, and 45 Fig. 4, is a top or plan view of Fig. 2.

For the purpose of illustrating my invention I have shown in the accompanying drawings one form thereof which is at present preferred by me, since the same has 50 been found in practice to give satisfactory and reliable results, although it is to be understood that the various instrumentalities of which my invention consists can be variously arranged and organized and that 55 my invention is not limited to the precise arrangement and organization of the instru-

mentalities as herein shown and described.

Referring to the drawings in detail the reference numeral 1 designates a plate of rectangular configuration. This plate 1 is 60 provided with openings 2 for screw accommodation whereby the plate may be secured to the frame 3 of a window as clearly shown in Fig. 1. The plate 1 has preferably 65 formed integral therewith at its top a lateral extension 4 terminating at its top in a bearing 5, which bearing including said lateral extension 4 has a vertical opening or passage 6 extended entirely therethrough for a purpose to presently appear. Preferably 70 formed integral with the lower part of plate 1 and extended laterally therefrom is an extension 7 having a screw threaded opening arranged vertically therethrough to receive the screw threaded end of a spring barrel 75 8 containing a coiled spring 9. Also carried by a plate 1, arranged intermediate the extensions 4 and 7 and provided with an aperture in alignment with the opening through extension 4 and the opening in spring barrel 80 8 is a lateral extension 10 forming a bearing 85 for a vertically disposed plunger 11. The plunger 11 is shown as being cylindrical in form, has its lower end engaging in a loose fit with the interior of spring barrel 8, and is provided at its upper end with a nib 12. This nib in the operation of the burglar alarm is adapted to strike the head of a percussion cap and cartridge 13 positioned in the opening through extension 4 90 and bearing 5. The plunger 11 is provided with a slotted portion 14. Having pivotal relation as at 15 with an extension 16 of plate 1 is a trip lever 17. This trip lever 17 is provided at its inner end with a bevelled portion 18 adapted to engage the slotted portion 14 of plunger 11, as clearly shown in Fig. 2.

A description will now be given of the mode of operation of the above described 100 device: To set the burglar alarm the lower sash 19 of a window in closed position is adapted to have rested upon the top thereof of the end 20 of the pivotal lever 17. The bevelled end 18 of which lever is positioned 105 within the slot 14 of plunger 11. In this position of parts no tension is being exerted upon spring 9. Upon an unauthorized person raising the window sash 19 the pivotal lever 17 is moved from the position shown 110 in full lines to that shown in dotted lines, during which movement plunger 11 has

been depressed to compress spring 9. As the window sash 19 is continued to be raised the bevelled end 18 of lever 17 disengages from the slot of plunger 11 whereupon 5 spring 9 forces plunger 11 forwardly so that the nib 12 is impelled against the percussion cap of cartridge 13 and exploding same to notify the occupants of the building that unauthorized entry is being attempted. The bevelled end 18 of lever 17 is maintained in a normal horizontal position by means of stop 20 carried by plate 1.

Having thus described my invention, what I claim as new and desire to secure 15 by Letters Patent is:

1. In a device of the character stated, a plate provided at its lower portion with a barrel containing a coiled spring, a slotted plunger capable of vertical movement 20 with respect to said plate, the lower end of which plunger is loosely fitted within said barrel upon said spring, a lever pivoted to said plate, one end of said lever being adapted to engage within said plunger slot, which 25 lever when tripped being adapted to cause compression of said spring, means carried by said plate for limiting the movement of said lever and plunger and a percussion cap carried by the upper part of said plate in 30 register with said plunger.

2. In a device of the character stated, a plate adapted for attachment to a window frame provided at its lower portion with a barrel containing a coiled spring, a slotted plunger capable of vertical movement 35 with respect to said plate, the lower end

of which plunger is loosely fitted within said barrel upon said spring, means carried by the plate to guide said plunger, a lever pivoted to said plate, one end of said lever being adapted to engage within said plunger slot, which lever when tripped being adapted to cause compression of said spring, the end of said lever engaging said slot being bevelled so as to disengage from said 45 slot during downward movement of said bevelled end, means carried by said plate for limiting the movement of said lever and plunger and a percussion cap carried by the upper part of said plate in register with 50 said plunger.

3. In combination a window frame, a window sash, a plate secured to the window frame, a barrel containing a coiled spring carried by the lower end of said plate, a 55 slotted plunger paralleling said plate and having its lower end loosely fitted within said barrel upon said spring, a lever pivoted to said plate, one end of said lever engaging said slot and the other end of said lever lying in the path of travel of said window sash, whereby upon raising of said sash said lever is moved about its pivoted point to cause compression of said spring, means carried by said plate for limiting the movement of said lever and plunger and a percussion cap arranged in alignment with said 60 plunger and carried by the top of said plate.

In testimony whereof, I have hereunto signed my name.

GEORGE MARSHALL.
